UNITED STATES PATENT OFFICE.

JOHN T. FROST, OF DULUTH, MINNESOTA, ASSIGNOR TO CLYDE IRON WORKS, OF DULUTH, MINNESOTA, A CORPORATION OF MAINE.

THROTTLE CONTROL FOR GAS ENGINES AND THE LIKE.

Application filed October 7, 1924. Serial No. 742,261.

To all whom it may concern:

Be it known that I, JOHN T. FROST, a citizen of the United States, and a resident of Duluth, county of St. Louis, and State of Minnesota, have invented a new and useful Improvement in Throttle Controls for Gas Engines and the like, of which the following is a specification, the principle of the invention being herein explained and the best mode in which I have contemplated applying that principle, so as to distinguish it from other inventions.

The present improvements have more particular regard to the provision of means whereby it is rendered possible to accelerate as well as decelerate an internal combustion engine. It is of course quite common to provide an engine of this type with an automatic governor, the effect of which is to control the throttle valve and thus the supply of fuel to the engine as to maintain a substantially constant speed. However, in various fields of use it becomes desirable to provide, as indicated, means whereby the operator can assume control temporarily to speed up the engine during some special stage of operation, or conversely to decelerate the speed as for idling when it is desirable to maintain the engine running but with a minimum consumption of fuel.

To the accomplishment of the foregoing and related ends, the invention, then, consists of the means hereinafter fully described and particularly pointed out in the claims, the annexed drawing and the following description setting forth in detail certain mechanism embodying the invention, such disclosed means constituting, however, but one of various mechanical forms in which the principle of the invention may be used.

In said annexed drawing:—

Fig. 1 is a side elevation, partly diagrammatic in character, of certain essential parts of an internal combustion engine showing the present improved throttle control; and Fig. 2 is a front elevation of a portion of the control mechanism, viewing same from the right as shown in Fig. 1.

The control mechanism illustrated in the foregoing drawing is designed specifically for use with a gasoline motor driven hoist, for the general operation of which a normal engine speed of 1000 R. P. M., for example, will be found desirable. At times, however, when the hoisting mechanism is not in use,

it will be desirable to have the engine simply idle at a speed for example of 200 R. P. M., rather than to stop the engine and then start it again. On the other hand, there will be occasions in the operation of the hoisting mechanism when a speed higher than the normal speed just indicated will be desirable, in which event it is necessary to accelerate the engine by opening the throttle wider than the governor would normally open it.

In the specific construction illustrated, the only portions of the engine shown are the carburetor 1 and the automatic governor 2, both of which are of standard construction, so that it is considered unnecessary to illustrate the same in detail. Located in the intake manifold 3 that leads from carburetor 1 is the usual butterfly throttle valve (not shown), the stem 4 of such valve being provided with a lever 5 for operative purposes. The governor 2 is likewise provided with an operating arm or lever 6 which is connected by means of a link 7 with the throttle lever 5, and as explained above, the governor will be set to maintain the throttle valve in proper position to operate the engine at a predetermined speed.

Mounted at a convenient point on the engine, for example on the radiator casing 8, is a rock shaft 9, such rock shaft being shown as lying just behind and extending transversely across the radiator in order that the control mechanism about to be described may be located on the opposite side of the engine from that on which the carburetor and governor are located. This shaft 9 is provided on such last mentioned side with a lever arm 10 which is connected by means of a link 11 with the same throttle lever 5 wherewith link 7 is connected. The opposite end of the shaft is bent at right angles to form an integral lever arm 12 that projects forwardly a short distance beyond the radiator 8, as shown in Fig. 1, and is received in a guide slot 13 formed in a plate 14 attached to the radiator housing. Pivotally attached to the lower end of this plate is a cam 15 of quadrant form, provided at one corner with an operating handle or knob 16. Normally said cam will lie in the downwardly depending position illustrated in full lines in Fig. 2, but when desired, it may be oscillated in a counter-clockwise direction to occupy the position shown in dotted out-

line in said figure (see also full line and dotted positions in Fig. 1).

The operation of my improved control device may now be briefly set forth. The 5 positions in which the several parts of the device, and particularly the throttle lever 5, governor lever 6 and control levers 10 and 11 with respective connecting links, are shown in full lines in Fig. 1 are those occupied 10 when the throttle is open, these positions being assumed when the operator presses manually downwardly on lever 12. Normally the parts occupy the positions indicated by the dash lines *a*, the throttle valve 15 in this condition of the device being under the control of the governor 2. The dot and dash lines *b*, on the other hand, indicate the positions of the parts in question when the quadrant cam 15 has been raised into position 20 to engage lever 12 and thereby raise the same above the position which it thus normally occupies.

The result of such last mentioned operation will be to decelerate the engine by more 25 nearly closing the throttle valve than is the case when under normal control by governor 2. It will be noted that the cam 15 has sufficient frictional engagement with the lever 12 to remain in such decelerating position 30 until it is positively returned to its inoperative position; also that by reason of the varying radius of the cam face, the idling speed at which the engine is held may be slightly varied to suit conditions. When the 35 quadrant cam 15 is in inoperative position, the engine may at any time be speeded up or accelerated by simply depressing lever 12 which will open the throttle beyond the point at which it is normally held by the 40 governor.

From the foregoing description, it will be seen that my device provides a very simple and convenient control supplementing without interfering with the action of the governor. Not only can the engine be readily accelerated to any speed above normal within 45 its range, but it can also be decelerated to any desired idling speed within the range of adjustment provided by the varying radius of quadrant cam 15.

Other modes of applying the principle of my invention may be employed instead of the one explained, change being made as regards the mechanism herein disclosed, pro-

vided the means stated by any of the following claims or the equivalent of such stated means be employed.

I therefore particularly point out and distinctly claim as my invention:—

1. In control mechanism for gas engines and the like, the combination with a throttle valve and a governor normally maintaining same in predetermined position; of a manually operable lever connected with said valve, whereby the setting of the latter may be varied optionally to accelerate or decelerate said engine from governor maintained speed, said lever being ordinarily freely movable so as not to affect the operation of said governor; and means adapted to be swung into the path of said lever to prevent its movement for acceleration but permit any one of a number of engine decelerating positions.

2. In control mechanism for gas engines and the like, the combination with a throttle valve and a governor normally maintaining same in predetermined position; of a manually operable lever connected with said valve, whereby the setting of the latter may be varied optionally to accelerate or decelerate said engine from governor maintained speed, said lever being ordinarily freely movable so as not to affect the operation of said governor; and a cam movable transversely of said lever and adapted to engage therewith to retain the same in any one of a number of engine decelerating positions.

3. In control mechanism for gas engines and the like, the combination with a throttle valve and a governor normally maintaining same in predetermined position; of a manually operable lever connected with said valve, whereby the setting of the latter may be varied optionally to accelerate or decelerate said engine from governor maintained speed; a plate formed with a slot wherein said lever is guided, the latter being ordinarily freely movable in such slot so as not to affect the operation of said governor; and a quadrant cam pivotally attached to said plate and adapted to be swung transversely of and into engagement with said lever so as to retain the same in any one of a number of engine decelerating positions.

Signed by me this 3rd day of October, 1924.

JOHN T. FROST.
